UNITED STATES PATENT OFFICE.

ROBERT BLAKELEY THURSTON, OF OIL CENTER, CALIFORNIA.

OIL-WELL PUMP.

1,318,513.

Specification of Letters Patent. Patented Oct. 14, 1919.

Application filed May 6, 1919. Serial No. 295,076.

To all whom it may concern:

Be it known that I, ROBERT B. THURSTON, a citizen of the United States, and a resident of Oil Center, in the county of Kern and State of California, have invented certain new and useful Improvements in Oil-Well Pumps, of which the following is a specification.

My present invention relates generally to oil well pumps, and more particularly to the apparatus for actuating the plunger rod of oil well pumps, my object being the provision of plunger rod actuating means which will automatically permit of vertical creasing of the plunger of the pump in the plunger casing or working barrel, and in this way avoid certain disadvantages in operation to which the pump and its connections are subject at the present time.

It is a well known fact that in all pumping oil wells there is an inclination for sand to drain from the oil veins into the casing or working barrel of the pump. This sand in the ordinary construction is packed down hard by the plunger, gradually filling the working barrel until either the plunger refuses to move or will not make a full stroke. This condition requires three men six or eight hours to pull out the rods and tubing, clean out the hard packed sand and replace the worn parts of the pump. A new well often "sands" five or six times during a week, making a large expense for labor and time lost from pumping through the disadvantage above noted.

In carrying out my invention, I provide a device which is so constructed and attached that when enough sand accumulates in the bottom of the working barrel to force the plunger up, the connection actuating the plunger rod, while allowing the plunger to fall downwardly as far as it will within the working barrel, will not force the plunger to the lowest point of its original travel, but will permit the plunger to seek a new higher level and will then impart the same length of stroke from each new succeeding higher level thus brought about. As a result of this construction, when enough sand has accumulated within the working barrel so that the plunger is forced up out of the barrel, the oil that is in the tubing of the well, will rush down through the working barrel and will wash out the sand, and it is then but the work of a few minutes to uncouple and drop the plunger back to

its original lowest level so that the pumping operation may be again started.

The means preferably employed for carrying out the above objects will be better understood from the following description thereof, reference being made to the accompanying drawing in which:

Figure 1 is a side view, more or less diagrammatic, illustrating the complete pumping arrangement,

Fig. 2 is a top plan view of the adjustable gripping device, and

Fig. 3 is a longitudinal section through the device shown in Fig. 2.

Referring now to these figures, and particularly to Fig. 1, my invention has to do with an oil well pump in which the plunger appears at 10, working within a barrel 11, from the upper end of which the pump casing 12 rises, the plunger being connected to a plunger rod 13 extending upwardly through the casing 12 and above the upper end of the casing, for engagement by the means utilized for bringing about vertical reciprocation of the pump rod.

The means I preferably employ include a walking beam or beam lever 14, fulcrumed at a point 15 above the surface, with one end slotted to receive the upper end of the rod 13, and with its opposite end actuated to and from any suitable source of power.

My invention also proposes the use of some adjustable gripping device upon the upper portion of the plunger rod 13 above the adjacent end of the beam lever 14 and to this end I may utilize a particular gripping device as shown in Fig. 3, having a tubular body 16 from which project diametrically outstanding arms 17 adapted for engagement by the respective end of the beam lever 14 in the upward movement of the latter. The body 16 has the lower portion of its vertical bore of conical form, the lower smaller end of which is but slightly larger than the plunger rod 13. The upper end of the bore of the body 16 is moreover closed by a cap 18 having a central opening through which the plunger rod also passes, and having openings at opposite sides of its central opening, to receive vertically therethrough the upper end of staples 19 forming handles and projecting upwardly from the upper ends of a pair of semi-cylindrical gripping members 20, whose inner surfaces are provided with gripping teeth 21, and whose outer surfaces are tapered to accord

W. J. TURNER.

STEAM HEATING APPARATUS.
